MECHANISM FOR TRANSFERRING
GLASSWARE

Arthur W. Beeson, Washington, Pa., assignor to
Hazel-Atlas Glass Company, Wheeling, W. Va.,
a corporation of West Virginia

Application February 7, 1934, Serial No. 710,160

13 Claims. (Cl. 198—22)

The invention relates particularly to means for transferring glassware from one conveyer to another, and steadyng the ware during its movements so that it will not topple over.

5 For the purpose of illustration the invention is shown in combination with an intermittently rotated escalator and a continuously rotating disc conveyer, both of which are old and per se form no part of the present invention. The escalator is of a well known type having a plurality of segment plates which are rotated intermittently; the plates being successively elevated from the plane where they receive the ware from the forming machine to the plane of the conveyer which is to carry the ware to the leer. As each plate reaches the plane of the conveyer, a revolving disc in this particular instance, the piece of ware is moved from the plate to the conveyer. The movements of the escalator tend 10 to topple the ware over, and there is also a tendency for it to topple over while being moved from the escalator to the leer. Also, it is necessary to have blasts of cooling air blowing in various directions, and these blasts often topple 15 over ware of certain types.

An object of the present invention is to provide a mechanism which will hold the ware steady while it is being deposited on the escalator, while it is being carried by the escalator up to the plane of the conveyer, and while it is being transferred from the escalator to the conveyer.

Various objects and advantages of the invention will be apparent to those skilled in the art from the following detailed description when taken in connection with the accompanying drawings; in which,

Figure 1 is a perspective view of the mechanism.

40 Figure 2 is a perspective view of the means for operating the transfer arm and associated parts.

Figure 3 is a plan view showing the position of various parts when an article is about to be transferred from the escalator to the revolving disc; and

Figure 4 is a side elevational view showing two pair of steadyng and transferring arms, for particular use with tall ware.

Referring to the drawings in more detail, 50 numeral 1 indicates a rotary disc conveyer arranged in front of a leer 2. The function of this conveyer is to carry the ware across the front of the leer, and it will be understood of course that an endless belt conveyer or any desired type of conveyer can be employed in

place of the disc conveyer shown. As the ware is carried in front of the leer, rows are successively fed into the leer by any desired means, as by a pusher arm 3 of a leer loader (not shown).

5 Numeral 4 refers generally to an escalator for elevating the ware delivered from a forming machine to the plane of the conveyer 1. The escalator may be of any desired type, but for purposes of illustration there is shown a well known type having a plurality of segment plates 5. The escalator is rotated step by step in timed relation with the glass forming machine (not shown). This step by step movement in timed relation with the forming machine is usually effected by means of a gear 6 which meshes with a gear (not shown) on the forming machine and with a gear 7 on the escalator. As the molds of the forming machine come to the delivery station the bottles or other articles are removed and placed on the segment plates 5, preferably by some form of take-out device such as diagrammatically illustrated in Figure 1 and referred to by numeral 8. The segment plates are elevated one step each time the escalator is rotated one step; and when each segment plate comes to a stop in the plane of the conveyer, the ware is removed. The means for steadyng the ware while it is being deposited upon the escalator and transported thereby, for transferring the ware from the escalator to the conveyer, and for 10 steadyng the ware during this transfer, will now be described.

Secured to each of the segment plates 5, adjacent the inner ends thereof, is a member 9 to which is secured a vertically extending rod 10. 15 Two brackets 11 and 12 are adjustably clamped to the rod 10 by means of set screws 13 and 14; and rods 15 and 16 are adjustably mounted in the brackets by means of set screws 17 and 18. The rods 15 and 16 carry at their outer ends 20 article receiving forks 19 and 20, of substantially V-shape. The bottles or other articles, when delivered from the forming machine to the escalator by the take-out device, are received by these fork members which steady the article while being released by the take-out device, and also steady it and prevent it from being toppled over by the blasts of cooling air or by the movements of the escalator. The forks 19 and 20 can be adjusted 25 in and out, and can be rotatably adjusted by the set screws 17 and 18; and they can be adjusted about the rod 10 and arranged at the desired height by the set screws 13 and 14, so that they will take care of ware of various sizes and shapes. 30

- As described above the forks 19 and 20 steady the ware and maintain it in proper position while it is being placed on the escalator and while it is being transported by the escalator to the point where it is to be transferred to the disc 1 or other conveyer for carrying it across the front of the leier. The means for transferring the ware from the escalator and for steadyng the ware during such transfer will now be described.
- 10 Numeral 21 refers to a transfer arm which is so positioned that it will be in back of each piece of ware successively brought to the transfer station. This arm is clamped or otherwise secured to a shaft 22, and this shaft is periodically rotated 10 in opposite directions to oscillate the transfer arm 21, by means to be described hereinafter.

Attached to and movable with the arm 21 is a bracket 23, in which bracket is mounted a clamp 24. This clamp can be vertically and rotatably 20 adjusted by means of a set screw 25. The clamp 24 carries two brackets, 26 and 27. Mounted in bracket 26 is a clamp 28, which can be vertically and rotatably adjusted by means of set screw 29; and mounted in bracket 27 is a clamp 30 which 25 can be vertically and rotatably adjusted by means of set screw 31.

Mounted in the clamp 28 is a rod 32, which can be adjusted longitudinally and rotatably by means of the set screw 33. This rod 32 leads to a 30 point adjacent the end of the transfer arm 21, and the end of the rod is turned to form an abutment 34. This rod is termed a stop and steadyng rod, and its functions will be best understood by reference to Figure 3. In this figure a glass 35 container A is shown at the transfer station ready to be transferred to the continuously revolving disc 1. It will be noted that the container is arranged in the forks 19 and 20, that the transfer arm 21 is in back of the container, and that the 40 stop and steadyng rod is in contact with one side of the container. This rod is accurately adjusted for the particular ware being handled, so that just as each segment plate 5 comes to a stop at the transfer station, the abutment 34 will lightly 45 engage the container and arrange it snugly between the abutment, the tines of the forks and the transfer arm 21. Thus the container is steadied and properly positioned when it is brought to a stop, ready to be transferred. The 50 transfer arm 21 is now swung over to the conveyer 1, by means to be described hereinafter, and of course the stop and steadyng rod 32 travels with it, so that the container is carried through an arc, with the transfer arm on one side of the container 55 and the abutment 34 on another side thereof. Thus the container is steadied throughout its transfer.

To assist in steadyng the articles as they are placed on the disc 1, and also to assist in properly 60 aligning the articles on the disc, there is preferably provided a guide and steadyng member 35, having in the specific form illustrated, three fingers 35'. This member is mounted in a clamp 36 and can be adjusted longitudinally and rotatably by means of a set screw 37. The clamp 36 is carried by a bracket 38, and the clamp can be 65 rotatably adjusted or be adjusted up or down by means of a set screw 39. Thus the steadyng and guide member 35 with its fingers 35' can be adjusted to any desired position; and when a bottle or other article is transferred to the disc as hereinbefore described, it will be prevented from toppling over by these fingers.

In the handling of tall ware, it is desirable to 75 use two pair of transfer arms and steadyng rods,

In Figure 1 the mechanism for mounting the extra pair is shown, but the upper transfer arm and associated steadyng rod have been omitted from this figure for the sake of clearness, but are shown in Figure 4. The upper transfer arm is indicated by numeral 40, and is mounted in clamp 30. This arm can be adjusted longitudinally and rotatably by means of set screw 41. The upper stop and steadyng rod is indicated by numeral 42, and this rod is provided with an abutment 43 10 at its end. The rod 42 is mounted in clamp 24, and the rod can be longitudinally and rotatably adjusted by means of the set screw 44. The upper pair of elements 40 and 42 correspond in function with the lower pair of elements 21 and 32, and further description thereof is accordingly unnecessary; it being understood that the elements 40 and 42 are particularly used with tall ware, and that they can be adjusted vertically, as well as in other directions, to suit the particu- 20 lar ware being handled.

To assist in properly positioning the ware on the escalator between the forks 19 and 20, there may be provided a guide rod 45 which is adjustably mounted in a clamp 46 by set screw 47. 25

The apparatus for periodically oscillating the transfer arm 21 and associated parts will now be described; but it will be understood, of course, that any desired means may be employed for this purpose. 30

Numeral 48 refers to an air cylinder which operates the piston rod 49. Air pipes 50 and 51 lead to opposite ends of the cylinder, and the admission of air under pressure to opposite ends of the cylinder may be controlled by cams (not 35 shown) timed with the forming machine; or if the apparatus is used with a Lynch machine then the air cylinder is controlled by the valve which controls the Lynch machine. The line 50 is preferably provided with a cushioning valve 52 to 40 cushion the operative stroke of the transfer arm 21.

A connecting rod 53 has one of its end pivotally connected with the piston rod 49, and its other end pivotally connected with an arm 54 45. clamped or otherwise secured to the shaft 22 which carries at its upper end the transfer arm 21. Thus when air under pressure is admitted to the left end of the cylinder 48 (Fig. 2) the transfer arm 21 is swung to its inoperative position, and when the pressure is admitted to the right end of the cylinder the transfer arm and associated parts are given their operative stroke to transfer the bottle or other article from the escalator to the disc 1; this stroke being cushioned by the valve 52 in line 50 through which the air from the left end of the cylinder is exhausting during this stroke. 50

The disc conveyer 1 is continuously rotated by any desired means, as by motor 55, reducing gear 60 56, worm gear 57 and shaft 58.

A very brief description of the operation of the apparatus will be sufficient, as the functions of the various elements have been made clear in connection with the description of the apparatus. The articles are successively removed from the molds of the forming machine and placed on the segment plates of the escalator by any desired means, as by the take-out device 8. The forks are so positioned and adjusted that they 70 will receive each article deposited on the escalator, and will prevent the article from toppling over when released by the take-out device. The step-by-step movement of the escalator elevates the articles to the plane of the disc 1 or other 75

conveyer for carrying the ware across the face of the leer. The articles while on the escalator are subjected to blasts of cooling air from various directions; and these blasts together with the movements of the escalator, tend to topple over the ware, particularly ware of certain types. The forks firmly maintain the ware in an upright position while being deposited on the escalator and while being transported by the escalator to the transfer station.

As each bottle or other article comes to a stop at the transfer station, the transfer arm 21 is in back of the bottle and the abutment 34 of the steadyng rod 32 engages one side of the bottle, so that with the forks the bottle is steadied in several directions. The air cylinder 48 now operates the piston rod 49 to cause the transfer arm 21 and the steadyng rod 32 to be swung over to the continuously revolving disc 1, thereby carrying the article through an arc to a position on the disc. And of course the bottle is steadied and prevented from toppling over during this transfer by the steadyng rod 32. As previously mentioned, and as illustrated in Fig. 4, two pair of transfer arms and steadyng rods are preferably employed in the handling of tall ware.

As each piece of ware reaches the disc 1 it is prevented from toppling over by the fingers 35 of the steadyng member 35. This member also assists in properly aligning the articles as they are carried forward by the disc, so that the articles are in a well formed line when they pass in front of the leer, and are thus properly positioned to be swept onto the leer conveyer by the pusher arm 3 or other suitable leer loading device.

From the foregoing description it will be apparent to those skilled in the art that I have devised simple and inexpensive means by which the ware delivered from a forming machine is steadied and prevented from toppling over while being placed on the escalator, while being transported by the escalator, and while being transferred from the escalator to the conveyer which carries the ware across the face of the leer. While I have particularly described the invention in connection with an escalator, yet it will be apparent that some features of the invention are in no manner limited to use with an escalator, but are of general application in the transfer of glassware from one conveyer to another. And while the particular apparatus illustrated has been described in considerable detail, yet it is obvious that many changes and modifications may be made without departing from the spirit of the invention, and all such changes and modifications are intended to be included within the scope of the appended claims.

Having fully described the invention, what I claim is:

60 1. Apparatus for transferring glassware, including an escalator having a plurality of segments for elevating ware to the plane of a conveyer, an open-sided ware steadyng member mounted on each segment, a movable arm in substantially the plane of the conveyer, and means for moving said arm to transfer the ware when the ware reaches the plane of the conveyer.

70 2. Apparatus for transferring glassware, including an escalator having a plurality of segments for elevating ware to the plane of a conveyer, an open-sided ware steadyng member mounted on each segment, an oscillatable arm in substantially the plane of the conveyer for removing ware from the escalator, and means for

oscillating said arm to transfer the ware when the ware reaches the plane of the conveyer.

3. Apparatus for transferring glassware, including an escalator having a plurality of segments for elevating ware to the plane of a conveyer, substantially V-shaped steadyng members mounted on the segments and adapted to receive the ware from a forming machine, a movable arm in substantially the plane of the conveyer, and means for moving said arm to transfer the ware when the ware reaches the plane of the conveyer.

4. Apparatus for transferring glassware, including an escalator having a plurality of segments, substantially V-shaped steadyng members mounted on the segments, means for adjusting the members vertically and horizontally, and means for removing the ware from the members.

5. Apparatus for transferring glassware, including a rotatable carrier, a movable arm for transferring ware from the carrier, a ware steadyng abutment associated with said arm, the rotation of the carrier bringing an article into cooperative relation with the arm and abutment, and means for moving the arm and abutment to transfer the article from the carrier.

6. Apparatus for transferring glassware, including a rotatable carrier, a movable arm for transferring ware from the carrier, a ware steadyng abutment associated with said arm, means for adjusting the position of the abutment with respect to the arm, the rotation of the carrier bringing an article into cooperative relation with the arm and abutment, and means for moving the arm and abutment to transfer the article from the carrier.

7. Apparatus for transferring glassware, including an intermittently rotated carrier, a movable arm for transferring ware from the carrier, a ware steadyng member associated with said arm, said member so positioned that an article is substantially in contact therewith when the carrier stops, and means for moving the arm and steadyng member to transfer the article from the carrier.

8. Apparatus for transferring glassware, including an intermittently rotated carrier, an oscillatable arm for transferring ware from the carrier, a ware steadyng member associated with said arm, said member so positioned that an article is substantially in contact therewith when the carrier stops, and means for oscillating the arm and carrier to transfer the article from the carrier.

9. Apparatus for transferring glassware, including an escalator for elevating ware to the plane of a conveyer, a movable arm in substantially the plane of said conveyer, a ware steadyng member associated with said arm, and means for moving the arm and member to transfer the ware when the ware reaches the plane of the conveyer.

10. Apparatus for transferring glassware, including an escalator having a plurality of segments, a ware steadyng member mounted on each segment, a movable transfer arm, a ware steadyng device associated with said arm, and means for moving said arm and ware steadyng device to remove ware from the escalator.

11. Apparatus for transferring glassware, including an escalator having a plurality of segments, a substantially V-shaped ware steadyng member mounted on each segment, an oscillatable transfer arm, a ware steadyng abutment

- associated with said arm, means for adjusting the abutment with respect to the arm, and means for moving the arm and abutment to remove ware from the escalator.
- 5 12. Apparatus for transferring glassware, including a conveyer, an escalator for elevating ware to the plane of the conveyer, a movable arm for transferring ware from the escalator to the conveyer, a ware steadyng abutment associated with and movable with said arm, and a ware steadyng device over said conveyer adapted to steady ware delivered by said arm.
- 10 13. Apparatus for transferring glassware, including a conveyer, an escalator for elevating ware to the plane of the conveyer, said escalator having a plurality of segments, a ware steadyng member mounted on each segment, a movable arm for transferring ware from the escalator to the conveyer, a ware steadyng abutment associated with and movable with said arm, and a ware steadyng device over said conveyer adapted to steady ware delivered by said arm.

5 10 ARTHUR W. BEESON.
